UNITED STATES PATENT OFFICE

2,570,996

OIL BURNER

Murray Walshin, New York, N. Y., assignor to
 Silent-Flame Manufacturing Co., Inc., New
 York, N. Y., a corporation of New York

Application March 15, 1947, Serial No. 735,007

1 Claim. (Cl. 158—76)

1

The present invention relates to oil burning equipment and more particularly to oil burning equipment of the type utilized for heating purposes in homes, factories, and the like.

One of the difficulties or objections to be contended with in the operation of oil burning equipment is obtaining the most efficient or optimum combustion conditions for each particular installation. An ideal situation would result if it were practicable to "tailor make" each individual oil burner for the particular home and conditions where it is to be used; this, however, is not feasible. In actual practice one size or capacity of oil burner is used in or serves within a range of conditions. While under this practice an oil burner for a given range of conditions may perform fairly well when operated in a furnace, it frequently does not "fit" exactly into the particular installation so as to give optimum combustion. The most favorable intermixing of air and finely divided or atomized oil and the best shape and size of flame are frequently lacking. Resulting incomplete combustion causes the use of increased quantities of oil in order to obtain additional heat and this results in higher operating costs.

The present invention aims to overcome or minimize the above and other difficulties or disadvantages by providing a relatively simple means by which there may be obtained greatly improved combustion for any given oil burner installation.

An object of the present invention is to provide a new and improved oil burning mechanism.

Another object of the invention is to provide an improved oil burner adapted to extend the field of usefulness of the particular oil burner.

Another object is to provide an improved oil burning device, the parts of which may be selectively related to give increased combustion efficiency.

Still another object of the invention is to provide improved means adapted to facilitate obtaining a most desirable shape and size of flame.

Other and further objects of the invention will be obvious upon an understanding of the illustrative embodiment about to be described, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

2

Fig. 1 is a perspective view illustrating one form of the present invention;

Fig. 2 is a fragmentary sectional view illustrating part of the oil burner shown in Fig. 1;

Fig. 3 is a fragmentary view showing in greater detail a portion of the device illustrated in Fig. 2;

Fig. 4 is a top view of the portion of the oil burner shown in Fig. 2;

Fig. 5 is an enlarged fragmentary view illustrating in greater detail a portion of Fig. 4; and

Fig. 6 is a sectional view taken along the line 6—6 of Fig. 5.

Referring to Fig. 1 of the drawings there is shown an oil burner comprising a base 1 having a pedestal 2 extending upwardly therefrom and supporting a housing 4. The housing 4 has an electric motor 5 mounted at one side thereof adapted to drive a fan or blower (not shown) located within the housing 4; when in use the blower draws air from the atmosphere and forces it through a cylindrical blast tube 7 shown extending outwardly from one side of the housing 4. The motor 5 is also adapted to drive an oil pump or oil supplying means 8 which may be located at the opposite side of the housing 4; the oil pump may receive fuel oil from any suitable source of supply and, in the present embodiment, discharges it into a conduit or oil line 13. The housing 4 may be adjusted in height with respect to the base 1 by suitable threaded means or the like connected with the pedestal 2.

The present invention is directed more particularly to the combination of an improved blast tube 7 with certain other parts adapted to co-operate with it. The construction of this tube and its co-operating parts will now be described.

The blast tube is shown more particularly in Figs. 2 and 4 of the drawings and may comprise a cylindrical tube or shell 11 adapted to extend close to or through a furnace wall. Through the blast tube extends an axially disposed oil conduit or oil line 13. Air from the atmosphere is normally forced through the blast tube 11, around the outside of the oil conduit 13, by the previously referred to fan or blower rotated by the electric motor 5. Oil to be burned for furnishing heat is fed through the oil conduit 13 and discharged through suitable openings in a nozzle 14 connected with the oil conduit 13 by a coupling member 15.

The oil may be ignited by means of customary electrodes 16 disposed adjacent the nozzle 14, the electrodes being carried by suitable insulating bushings 17 and being connected by suitable wires or cables 18 with an exterior switch and source of electric current. The wires 18 may ex-

tend through a closely fitting opening 20 to thereby minimize leakage of air out of the casing 4 or blast tube 11 around the wires.

As the air passes through the blast tube it is given a whirling or cyclonic effect by vanes carried by a suitable vane unit 37 and end cone 23. These vanes are preferably similarly inclined or pitched so that each set of vanes rotates the air in the same rotary direction. Hence air emerging from the end cone 23 is rapidly whirling or rotating.

With oil burners the shape and size of the flame and the degree of combustion is considerably affected by the relationship of the blast tube which conveys air to the interior of the furnace and the oil tube and nozzle which furnish oil to the interior of the furnace. A blast tube generally carries vanes fixed in position at its outer end and an oil conduit with a nozzle fixedly positioned with respect to the blast tube and an end cone. The particular relationship of these parts greatly affects the shape and size of the flame in the furnace pot and the degree of combustion, these qualities being generally fixed for a particular oil burner.

In the present invention (Figs. 2 and 4) there is shown an inner cylindrical or tube-like member 25 telescopically or slidably fitted into the outer tube-like portion 11. The auxiliary tube 25 carries an end cone, with suitable vanes, adjacent its outer end and is adapted to be moved to and fro with respect to the tube portion 11 to vary the effective length of the blast tube, which tube is designated generally by the reference numeral 7 in Fig. 1. The effective length of the blast tube 7 and the spacing of the vanes 22 from the fuel nozzle 14 may thus be varied by shifting the tube 25 longitudinally. The outer tube 11 is provided with a longitudinally extending slot 26 through which extends a screw or bolt 27 threaded into the inner telescoping tube 25. The bolt 27 serves to limit the extent of longitudinal movement of the tube 25 with respect to the tube 11 and minimizes the possibility of accidentally moving the tube 25 outwardly so far as to disengage it from the outer tube 11. The bolt 27 may be tightened to securely lock the tubes together in an adjusted position.

While the extensible tube portion 25 is shown mounted interiorly of the tube portion 11, it will be clear that it could be of slightly larger diameter than the tube portion 11 so as to slide over the exterior of the tube 11.

The rearward part of the inner tube 25 is shown connected with an extension or rod 28 which projects rearwardly to a position in the blower casing 4. The extension or rod 28 may be attached by welding or any other suitable manner to the tube 25. Adjacent the end of the extension rod 28 the housing 4 is provided with a slot or opening 29, the relationship of the slot or opening to the rod 28 preferably being such that the rod or a portion of it overlies the slot 29; this overlying or covering feature tends to close or seal the slot 29 so that air forced to and through the blast tube does not escape outwardly through the opening 29.

A handle or arm 31 may be connected with the rod 28 so that the handle 31 projects through the slot 29 to facilitate longitudinal movement of the rod 28 and the blast tube extension 25 carried thereby. Of course, in order to move the blast tube extension 25 through the rod 28 and handle 31 it is first necessary to release the bolt 27 at the upper part of the blast tube; after the blast

tube 25 has been adjusted the bolt 27 may be tightened to maintain the desired adjustment. Preferably the handle 31 is connected with the rod 28 at a point removed from the extreme end thereof so that when the handle is moved to an extreme position adjacent the forward end 32 of the slot 29, a portion 33 of the rod 28 remains in overlying relationship with respect to the opening 29 to thereby prevent escape of air out through the opening 29.

The housing 4 may be supplied with suitable indicia 35 to facilitate obtaining desirable setting of the tubes with respect to each other and likewise the outer blast tube 11 may be furnished with suitable indicia 34 (Fig. 4) to facilitate obtaining the adjustment.

The foregoing described telescopic construction facilitates movement of an end cone 23 and its vanes 22 with respect to the oil conduit 13 and the nozzle 14 carried thereby and thus contributes toward obtaining a most favorable shape and size of flame in the furnace. The construction above described provides what may be termed a "rough" adjustment and facilitates positioning of the end cone 23 and its vanes 22 with respect to the wall of the furnace with which the burner is to be used.

In order to obtain a "finer" adjustment of the flame and to facilitate correct positioning of the nozzle 14 with respect to the end cone 23, the axial oil conduit 13 is also constructed and assembled for longitudinal positioning with respect to the blast tube.

As shown, the oil conduit 13 is supported adjacent one end thereof by a vane unit 37 and it may be held in assembled relationship with the vane unit by a set screw 38. The vane unit 37 is adapted to be moved to and fro with respect to the walls of the outer tube; a slide fit facilitates movement of the vane unit 37 and the oil conduit 13 supported thereby. As previously described, the forward end of the oil conduit 13 is connected with a suitable discharge nozzle 14 by a coupling member 15. The opposite end of the oil conduit 13 is provided with a bend or curve 40 (Fig. 4) so that the rear portion of the conduit 13 extends laterally with respect to the blast tube and projects through a side wall of the housing 4 at a position adjacent the slot 29 and controlling handle 31 which serves to facilitate adjustment of the blast tube extension 25. The laterally extending portion of the conduit 13 projects through a slot or enlarged opening 41 in the housing wall and is shown carried by a boss 42 of a plate member 43. The plate member 43 is provided with an adjustment slot 44 through which extends a bolt 46. The bolt 46 has a head portion overlapping the side walls of the slot 44 so that it may be utilized to support the plate member 43 and to lock it into position, as will be hereinafter described.

The outer end of the laterally extending portion of the conduit 13 is shown connected with the oil conduit 10 by a coupling member 47 so that oil forced through the conduit 10 by the pump 8 passes into the conduit 13 and through it to the nozzle 14. The conduit 10 which connects the axial conduit 13 with the oil pump 8 is preferably formed with curves of relatively large radius. When the bolt 46 is loosened the plate member 43 may be shifted longitudinally with respect to the blast tube 7 to thus correspondingly move the axially disposed oil conduit 13 along the blast tube. The vane unit 37 which supports the oil conduit 13 within the blast

tube slides along the tube and maintains the oil conduit in centrally disposed position. The enlarged bearing surface provided by the boss 42 of the plate member 43 minimizes cutting or digging into the conduit 13; this is desirable as the conduits are generally made of copper and hence are relatively soft. Longitudinal movement of the plate member 43 and the oil conduit 13 which projects thereinto is facilitated by bends of relatively large radius provided in the connecting conduit 10. These bends flex or yield sufficiently to allow movement of the plate 43. When a correct adjustment has been obtained the guiding and clamping bolt 46 may be tightened to maintain the adjusted relationship of the oil conduit 13 within the blast tube.

As pointed out hereinabove, a relative rough adjustment may be obtained by shifting the blast tube extension 25 and a finer adjustment may be obtained by thereafter shifting the conduit 13. This feature is desirable as the burner may first be installed and adjusted to approximately correct position by shifting the blast tube extension 25. Thereafter a more perfect or finer adjustment may be made by shifting the conduit 13 and its nozzle 14 with respect to the vanes 22 of the end cone 23.

Preferably the vanes 22 of the end cone 23 and the vanes of the vane unit 37 are of the same or similar inclination or pitch so that when air passes through the vane unit 37 it is given a whirling motion which is even further enhanced upon striking the vanes 22 of the end cone 23.

If desired the plate 43 may be provided with an arrow or indicating mark 48 and the housing wall may be provided with suitable indicia or markings 49 to facilitate obtaining a correct adjustment or to obtain a correct resetting.

It will be seen that the present invention provides a new and improved oil burning mechanism which is adapted to facilitate accurate adjustment of a flame. The flame may be focused to make it longer, shorter, wider, flatter, thinner or to otherwise change it into various desirable shapes and sizes. The accurate adjustment and control of the flame provided by the rough adjustment of the end cone carried by the blast tube extension, and the more delicate or finer adjustment facilitated by the movable oil conduit, contribute toward more efficient and complete combustion of fuel oil and hence result in decreased oil consumption and increased efficiency. The improved combustion provides a cleaner furnace and reduces the amount of smoke generated. The construction is adapted to incorporation in oil burners of different sizes and the operating parts may be made in any suitable dimensions and from any suitable materials. The parts are of relatively simple construction and

delicate adjustment of the flame may readily be made.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

An oil burner device of the class described comprising the combination of a fixed air guiding tube having an opening through a side wall thereof and a slot through a side wall thereof, a movable air guiding tube provided with a set of air guiding vanes adjacent the outer end thereof and having uninterrupted exterior and interior wall portions extending a substantial distance rearwardly from said air guiding vanes, said movable air tube being telescopically slidably along the fixed air tube, a longitudinally movable oil conduit disposed centrally within said air tubes, a set of air guiding vanes secured to and supporting said oil conduit at the interior of said uninterrupted rearwardly extending portion of the movable air tube and slidable along the interior thereof upon longitudinal movement of said tube or upon longitudinal movement of said oil conduit, a portion of said oil conduit extending laterally through said wall opening of the fixed air tube for connection with an oil pump, and an arm connected with said movable air tube and extending through said slot through the fixed air tube side wall to a position a substantial distance outwardly of the fixed air tube for facilitating movements of the movable air tube.
